UNITED STATES PATENT OFFICE.

FRANK WAYLAND, OF SALEM, MASSACHUSETTS.

LEATHER-WORKING MACHINE.

1,355,437.

Specification of Letters Patent. Patented Oct. 12, 1920.

Application filed April 22, 1920. Serial No. 375,781.

To all whom it may concern:

Be it known that I, FRANK WAYLAND, citizen of the United States of America, and resident of Salem, in the county of Essex and State of Massachusetts, have invented new and useful Improvements in Leather-Working Machines, of which the following is a specification.

This invention relates to machines for stretching, pressing, putting out, and otherwise treating skins, hides and leather and consists in certain improvements hereinafter described on machines of the general character illustrated in Letters Patent of the United States issued to me Nos. 1,077,207; 1,090,895; 1,131,756; 1,204,914; and 1,214,852. In machines of the kind represented by the foregoing patents pinch rolls or feed rolls draw the skins between various forms of working elements for stretching, staking, softening, putting out, ironing, glazing or otherwise working the skins. The pinch rolls themselves in certain instances also serve both as feed rolls and working elements. For performing work of this kind it is essential that very considerable pressure be exerted on the skin by the pinch rolls in order properly to feed the skin through the machine, to squeeze out the water and press the skin, and to maintain the necessary tension on the skin. Hitherto, this pressure between the pinch rolls has been exerted mainly by applying power to the swinging frame which carries the separable pinch roll or rolls to force the latter directly against the positionally fixed roll or rolls. This requires the expenditure of a large amount of power directly applied to the swinging frame to push one roller against another. In some instances the pinching pressure has been supplemented by additional mechanism for applying an increased final pressure after the rolls have been brought into operative relation.

It is the principal object of the present invention to improve the construction and co-action of the pinch rolls to attain high pressure between the pinch rolls with a more simple and easily operable construction and with the expenditure of relatively little power. Other features of the invention will be hereinafter described and more particularly pointed out in the claims.

In the accompanying drawings which illustrate one embodiment of the invention:

Figure 1 is a vertical section of such parts of the machine as are necessary to an understanding of the invention, certain parts being shown in elevation;

Fig. 2 is a front elevation of one end of the machine;

Fig. 3 is an enlarged detail in end elevation of the top of the machine showing the separable roll carried by the swinging arm in open position; and

Fig. 4 is a diagrammatic view illustrating one of the pairs of stretching and tension belts in plan.

The main frame of the machine 1 carries all the working parts and is preferably constructed of castings. A pair of rocking frames 2, 2, one at each end of the main frame, are mounted to rock or oscillate on shaft 3 which is a driving shaft journaled at its ends at the top of the main frame. A gear 4 keyed to shaft 3 meshes with gears 5 and 6 keyed respectively to shafts 7 and 8. Shafts 7 and 8 are journaled in the rocking frames 2—2 and carry pinch rolls 9 and 10 which extend between the rocking frames. The journal boxes 11 and 12 for shafts 7 and 8 are mounted respectively to slide in ways 13 and 14 in the rocking frames 2 and are pressed downward and inward by stiff coil compression springs 15 and 16, the force of whose compression may be regulated by adjusting screws 17 and 18 mounted on the rocking frames 2 at the ends of the slide ways 13 and 14. The slide ways 13 and 14 are preferably disposed at approximately a right angle to each other.

The rear shaft 7 extends through and beyond the machine frame and has fixed to its outer end a long toothed gear wheel 19 which serves both as a driving gear and as a finder gear as hereinafter explained.

At each end of the machine just outside of the main frame is a swinging arm 20 pivoted on shaft 23 at the lower part of the machine. Extending between the upper ends of the two swinging arms 20 is a shaft 21 which carries pinch roller 22. Shaft 21 also extends through slot 37 in the machine frame and has fixed to its outer end a long toothed gear 24 which meshes with gear 19 when the parts are in operative position as shown in Figs. 1 and 2.

The pinch rolls 9, 10 and 22 may be covered with materials suited to the work to be performed. For example they may be covered with felt, cloth, or rubber, as desired,

for stretching, drying, pressing, or putting out skins, or if the machine is to be used for ironing and finishing one of the rolls, preferably roll 22, may be a metal roll with provision for heating it in the usual manner.

A presser bar 25 carried by a pair of short swing arms 26 journaled to the machine frame on studs 27 is urged against the pinch roll 22 when the latter is in working position by a suitable number of adjustable coil springs 28. These coil springs have their abutments against brackets 29 which are fastened to a cross rod or shaft 30 extending from side to side of the machine. The working face of the presser bar 25 is provided with inclined vanes 3 diverging from the center of the machine to stretch and work out the skin laterally in each direction at the center as it passes between the presser bar 20 and the pinch roll 22.

Below the pinch rolls are two pairs of stretching and tension belts, the belts of each pair being mounted end to end and traveling in opposite directions from their adjacent ends. One pair of said belts 32, 33 is carried and driven by sprocket wheels 34 mounted on a cross bar 35 which extends between the swinging arms 20. The other similar pair of belts with which the first pair co-operates 30 is similarly mounted and driven on a fixed part of the machine frame, one belt of the latter pair being shown at 36, Fig. 1. Said belts are substantially similar to those shown in my said Letters Patent No. 1,214,852 and 35 as neither the belts nor the mechanisms by which they are mounted and driven, form part of the present invention, no further description of them will be necessary.

The mechanism for operating the swinging arms 20, with the parts carried thereby, to open and close the pinch rolls likewise forms no part of the present invention and need not be herein described. Any well known or preferred mechanism for this purpose may be used such as that indicated in my Patent No. 1,077,207. Suffice it to say that said swinging arms 20 swing forward to open in an arc represented approximately by the slot 37 in the machine frame.

50 The shaft 3 is the driving shaft for the pinch rolls and may be rotated from any suitable source of power (not shown). When shaft 3 is driven in the direction of the arrow, that is in a clockwise direction as viewed in Fig. 1, it will turn shafts 7 and 8 through gears 5 and 6 together with their rolls 9 and 10 in a counter-clockwise direction as indicated by arrows, and gear 19 on shaft 7 meshing with gear 24 on shaft 21 55 will turn the latter together with pinch roll 22 in a clockwise direction.

In operation, assuming that the swinging frame composed of arms 20 has been swung forward, the roll 22 will be opened or separated from the other pinch rolls as shown

in Fig. 3 and the stretching and tension belts 32, 33 will be likewise separated from the corresponding opposed belts mounted on the fixed machine frame. The skin is then laid into the machine behind or on top of the pinch roll 22 and belts 32, 33, and the swinging arms 20 will be swung to operative or closed position as shown in Fig. 1. As the frame 2 is free to rock or oscillate the pinch roll 22 will engage both rolls 9 and 10 before exerting any considerable pressure on either and the finder gear 24 with long pointed teeth will readily engage and mesh with the similar finder gear 19 on shaft 7. Continued movement of the swinging frame causes the several pinch rolls acting one upon another to roll into place, the springs 15 and 16 compressing as the pressure increases, and the oscillating frame 2 finally rocking into the position shown in Fig. 1 when the pinch roll 22 reaches its final working position. This action of the oscillating frame 2 in conjunction with the swing arms 20 resembles the action of a toggle joint exerting very great pressure between the rolls 9, 10, and the roll 22 with the expenditure of comparatively little power for swinging the roll 22 into place. The action of the closing movement is assisted by the pressure of the front roll 10 which bears against the following side of the roll 22 when the latter by pressing against roll 9 swings or rocks the oscillating frame 2. It will be seen that the principle of the toggle joint results from the organization and arrangement of parts in such manner that the component of the force, applied in a tangential direction for bringing the rolls to working position, exerted radially of the rocking frame and the swinging frame greatly exceeds the transverse component.

When the roll 22 is in closed position it also bears against the presser bar 25 somewhat compressing the spring 28.

When in working position the downward pressure of the pair of rolls 9 and 10 against the roll 22 is substantially balanced and is exerted approximately in a line connecting the pivots of the rocking frame 2 and the swinging arms 20 so that comparatively little power is required to roll the parts into working position notwithstanding they are subjected to high pressure one against the other.

The skin is now tightly pinched between rolls 10 and 22, rolls 9 and 22, bar 25 and roll 22 and between the stretching and tension belts 32, 33 and their corresponding opposed pair on the fixed frame of the machine. The driving shaft 3 being operated, the pinch rolls will feed the skin upward and out of the machine squeezing, pressing, stretching and working it out in conjunction with the presser bar 25 and its divergent vanes which spread and stretch the

skin laterally and in conjunction with the stretching and tension belts which not only straighten and stretch the skin laterally before it passes to the pinch rolls but also put 5 a longitudinal tension on it as it is pulled upward by the pinch rolls.

I claim:

1. A leather working machine comprising a rocking frame, pinch rolls journaled 10 on the rocking frame, and a swinging frame having a pinch roll journaled at the free end thereof coöperating with the pinch rolls on the rocking frame to rock the latter when the swinging frame is forced into working 15 position and to exert high pressure between the coacting pinch rolls, the parts being so organized and arranged that the component of the force applied for bringing the rolls to working position exerted radially of the 20 rocking frame and the swinging frame greatly exceeds the transverse component, according to the principle of the toggle joint.

2. A leather working machine comprising a rocking frame, pinch rolls journaled 25 in yielding bearings on the rocking frame, and a swinging frame having a pinch roll journaled at the free end thereof coöperating with the pinch rolls on the rocking 30 frame to rock the latter when the swinging frame is forced into working position and to exert high pressure between the coacting pinch rolls, the parts being so organized and arranged that the component 35 of the force applied for bringing the rolls to working position exerted radially of the rocking frame and the swinging frame greatly exceeds the transverse component, according to the principle of the toggle 40 joint.

3. A leather working machine comprising a rocking frame, a pair of pinch rolls journaled on the rocking frame, one at each side of the pivot of the rocking frame, and a 45 swinging frame having a pinch roll journaled at the free end thereof coöperating with the pinch rolls on the rocking frame to rock the latter when the swinging frame is forced into working position and to exert 50 high pressure between the coacting pinch rolls, the parts being so organized and arranged that the component of the force applied for bringing the rolls to working position exerted radially of the working frame 55 and the swinging frame greatly exceeds the transverse component, according to the principle of the toggle joint.

4. A leather working machine comprising a rocking frame, pinch rolls journaled on 60 the rocking frame, and a swinging frame having a pinch roll journaled at the free end thereof coöperating with the pinch rolls on the rocking frame to rock the latter when the swinging frame is forced into working 65 position and to exert high pressure between

the coacting pinch rolls, and a presser bar supported on the machine frame below the rocking frame, adapted to engage the pinch roll on the swinging frame when the latter is closed, the parts being so organized and 70 arranged that the component of the force applied for bringing the rolls to working position exerted radially of the rocking frame and the swinging frame greatly exceeds the transverse component, according 75 to the principle of the toggle joint.

5. A leather working machine comprising a rocking frame, pinch rolls journaled in yielding bearings mounted to slide in ways arranged at an angle to each other on the 80 rocking frame, and a swinging frame having a pinch roll journaled at the free end thereof coöperating with the pinch rolls on the rocking frame to rock the latter when the swinging frame is forced into working 85 position and to exert high pressure between the coacting pinch rolls, the parts being so organized and arranged that the component of the force applied for bringing the rolls to working position exerted radially of the 90 rocking frame and the swinging frame greatly exceeds the transverse component, according to the principle of the toggle joint.

6. A leather working machine comprising a rocking frame, a pair of pinch rolls journaled on the rocking frame, and a swinging frame having a pinch roll journaled at the free end thereof coöperating with the pinch rolls on the rocking frame to 100 rock the latter when the swinging frame is forced into working position and to exert pressure between the coacting pinch rolls, the front roll on the rocking frame being adapted to press on the following side of 105 the roll on the swinging arm during the closing movement of the latter.

7. A leather working machine comprising a rocking frame, a drive shaft on which the rocking frame is pivoted, a pair of pinch 110 rolls journaled on the rocking frame one at each side of the pivot of the rocking frame, gears fixed to said pinch rolls, a driving gear fixed to the drive shaft and meshing with both gears fixed to the pinch rolls, a 115 swinging frame having a pinch roll journaled at its free end coöperating with the pinch rolls on the rocking frame to rock the latter when the rolls are forced into working position and to exert high pressure between the coacting pinch rolls, and driving gears connecting said pinch roll on the swinging frame to one of the pinch rolls on the rock frame when the swinging frame is in closed position.

8. A leather working machine comprising a rocking frame, a drive shaft on which the rocking frame is pivoted, a pair of pinch rolls journaled on the rocking frame one at each side of the pivot of the rocking frame, 130

gears fixed to said pinch rolls, a driving gear fixed to the drive shaft and meshing with both gears fixed to the pinch rolls, a swinging frame having a pinch roll journaled at its free end coöperating with the pinch rolls on the rocking frame to rock the latter when the rolls are forced into working position and to exert high pressure between the coating pinch rolls, and driv-

ing and finder gears having elongated teeth 10 connecting said pinch roll on the swinging frame to one of the pinch rolls on the rocking frame when the swinging frame is in closed position.

Signed by me at Boston, Massachusetts. 15 this 10th day of April, 1920.

FRANK WAYLAND.
